UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed May 23, 1922. Serial No. 562,985.

My invention relates to draft rigging and more particularly stated, contemplates the production of a simple, strong and durable follower adapted to be cooperatively associated with the cushioning mechanism and a movable element of the draft rigging.

The principal object of my invention is to provide a comparatively light weight follower of maximum strength value which can be easily cast and readily inserted with small expenditure of labor between a movable element of the draft rigging and the cushioning mechanism, whereby the stresses to which the associated parts are subjected in service may be effectively resisted without distortion or deformation of said associated parts.

Another object of the invention resides in the provision of a draft rigging follower provided with a plurality of webs or flanges connected by a wall forming a bearing surface contacting a movable element of the draft rigging, and means for supporting and bracing said wall, said means terminating in open portions adjacent said bearing surface.

A further object of the invention is to provide a follower which can be easily inserted between the rear end of the cushioning mechanism and the interior face of the loop end of the yoke, said follower being formed with a front wall and a plurality of projecting vertical webs having intermediate portions of their rear edges united by a rear wall, said rear wall forming a relatively large bearing surface contacting the yoke and being braced by a plurality of horizontally arranged webs uniting said vertical webs, portions above and below said bearing surface being open to permit removal of the cores.

A still further object of the invention resides in the provision of a draft rigging rear follower provided with rearwardly projecting webs connected by a rear wall forming a bearing surface contacting the yoke member of the draft rigging, means for bracing said bearing surface, and means formed on the outermost rearwardly projecting webs for supporting the rear end of the yoke in horizontal alinement with said bearing surface.

With these and other objects in view, my invention consists in the construction and

arrangement of the several parts hereinafter described and pointed out in the claims.

In the accompanying drawings wherein similar reference characters designate corresponding parts in the several views:

Figure 1 is a view partly in plan and partly in horizontal section of a portion of the center sills or draft sills of a railway car showing my improved follower interposed between the rear of the cushioning mechanism and yoke member, said yoke member being shown contacting a back stop casting uniting the rear ends of the car sills.

Figure 2 is a vertical longitudinal sectional view through the center sills, back stop and yoke, my improved follower being shown in side elevation.

Figure 3 is an enlarged rear view in elevation of the follower.

Figure 4 is a vertical longitudinal sectional view through the follower on the line 4—4 of Figure 3.

Figure 5 is a horizontal transverse sectional view on the line 5—5 of Figure 4.

My improved follower is shown applied to a railway draft rigging in which the center sills or draft sills 1 are suitably connected at their inner ends by a back stop center filler casting 2. A forward wall 3 forming an abutment for the yoke 4 is provided on said back stop, said wall being suitably reinforced and braced to receive the buffing shocks, as will be understood. The cushioning mechanism is conveniently indicated by the dot and dash lines shown in Figures 1 and 2. My invention is shown and described as embodied in a rear follower member, but it will be understood that I do not limit the invention to a follower constructed for use only between the rear end of the yoke and the rear of the cushioning mechanism.

The follower 1 is formed with a vertical front wall 5, an intermediate portion thereof being cast relatively thicker and heavier, as at 6, to provide increased strength at the principal point of stress. Formed integrally with and projecting rearwardly from the front wall is a plurality of vertical flanges or webs 7, the central or intermediate webs extending rearwardly the full depth of the follower, and the outermost webs forming the side walls of said follower terminating short of said intermed-

ate webs, as shown. The upper portion of each rear edge of the intermediate webs is forwardly inclined, as indicated at 8, so as to permit the ready insertion and entry of the follower between the rear of the cushioning mechanism and the interior face of the loop end of the yoke member. The upper edges of the vertical web 7 are joined by a top web portion or flange 9, said portion forming a horizontal closure wall for the spaced hollow recesses or chambers 10 formed between said vertical rearwardly projecting webs 7 in the upper part of the casting. A bottom wall 11 extends rearwardly from the front wall 5, said bottom wall uniting the lower edges of the vertical webs 7 and forming a closure for the recesses or chambers 12 formed between said vertical webs 7 and adjacent the bottom of the casting.

The rear wall 13 of the follower is arranged intermediate the top and bottom portions thereof, said rear wall uniting intermediate portions of the rear edges of the rearwardly projecting vertical webs 7. Rounded or curved portions 14 are provided at the corners uniting the rear wall with the outermost vertical webs, said curved portions being arranged and adapted to fit within the rounded interior face of the yoke loop joining the side arms of said yoke, as shown in Figure 1. The rear wall 13 constitutes a relatively large and effective bearing area contacting the yoke whereby the drawing stresses are transmitted through the rear of the yoke to the cushioning mechanism and excessive loads transmitted to the car underframing without cutting or otherwise mutilating the yoke.

Means is provided for bracing said bearing surface, said means including the vertically arranged webs 7, thickened slightly, as shown at 15, and a plurality of transverse horizontally disposed webs 16 uniting the vertical webs 7 and the front and rear walls of the casting. A plurality of chambers or rectangular recesses 17 are formed between the intersecting vertical and horizontal webs, a series of transversely arranged and substantially aligned openings 18 being provided in the thickened wall portions 15 to lighten the casting and provide for the removal of the cores.

The follower is also provided with means at each side thereof for supporting the rear end of the yoke in horizontal alinement and contact with the bearing surface, said means including projections 19 arranged upon the outermost vertical webs 7 adjacent the front wall of the follower and adapted to form seats for the side arms of the yoke. The upper surface of the projections are disposed substantially in a horizontal plane passing through the lower edge of the rear wall. The projections 19 on the follower support

the yoke, and the follower is in turn slidably mounted upon a plate 20 connected to the draft sills by means of the bolts 21. The plate is shown as extending under the rear follower and under the rear end of the cushioning mechanism, and serves to support both of these elements of the draft rigging to permit their sliding movement when operating in service. Openings 22 are preferably provided in the front wall 5, said openings extending through to the respective upper and lower recesses or pockets 10 and 12 hereinbefore referred to.

It will be apparent that by means of the internal flanges and webs on a follower constructed in accordance with my present invention, one wall is so formed as to provide a full and complete bearing surface with which a movable element of the draft rigging may cooperate without mutilation and that all stresses to which the associated parts may be subjected in service are amply resisted by sufficient sections so economically arranged that the casting while possessing great strength is comparatively light in weight and is, moreover, a simple casting both to mold and cast.

The distance between the front and rear faces of the follower, that is, the depth or filler distance between the outer surface of the front wall 5 and the outer surface of the rear wall 13 is made to correspond with the difference between the standard distance of twenty-four and five-eighths inches, required between the rear end of the coupler butt and the front face of the draft yoke loop and the length of the cushioning mechanism to be used. Before this distance was standardized, the difference between it and the length of the cushioning mechanism could be made so small that a simple solid follower plate, such as shown at 19 in the Patent No. 1,097,738 to Symington, could be used or, if desired, the follower plate or plates could be dispensed with. With the standardization of this distance, the problem of filling the relatively large space, when a short cushioning mechanism is used, without unduly adding to the weight of the draft rigging, presented itself. This has been satisfactorily solved by the present device.

I claim:

1. A follower for railway draft rigging including longitudinally spaced opposite wall portions cooperatively associated with and embraced by the cushioning mechanism and one of the movable elements of the draft rigging, and a plurality of vertically arranged and a plurality of horizontally arranged webs or flanges uniting said wall portions, one of said wall portions forming a relatively large transversely extending bearing surface adapted to contact said movable element of the draft rigging.

and having open portions above and below said bearing surface.

2. A follower for railway draft rigging including longitudinally disposed opposite wall portions cooperatively associated with and embraced by the cushioning mechanism and one of the movable elements of the draft rigging, a plurality of vertically and horizontally arranged intersecting webs 10 uniting said opposite wall portions, one of said wall portions uniting the horizontal webs and intermediate edge portions of said vertical webs to form a relatively large transversely extending bearing surface 15 contacting said movable element of the draft rigging.

3. A follower for railway draft rigging including longitudinally disposed opposite wall portions cooperatively associated with 20 and embraced by the cushioning mechanism and one of the movable elements of the draft rigging, a plurality of intersecting webs uniting said opposite wall portions, said webs serving to brace the follower and arranged to form a series of substantially closed and a related and adjacent series of open recesses whereby a relatively light weight follower is provided in which the cores can be readily removed, one of said 25 wall portions being adapted to form a transversely extending bearing surface contacting the movable element of the draft rigging.

4. A follower for railway draft rigging 30 including longitudinally arranged opposite wall portions cooperatively associated with and embraced by the cushioning mechanism and one of the movable elements of said draft rigging, one of said walls being 35 formed with an intermediate face adapted to extend transversely and contact said movable element of the draft rigging, means including a plurality of webs for bracing said wall portion, and means provided on the 40 outermost of said webs for supporting the movable element of the draft rigging.

5. A follower for draft rigging including a wall extending the full height of said follower, a plurality of webs projecting from said wall and having their outer edges terminating in spaced vertical planes, and another wall uniting portions only of said outer edges, said last named wall forming a transverse bearing surface adapted to be 45 engaged by a movable element of the draft rigging.

6. A follower for draft rigging including a wall extending the full height of said follower, a plurality of webs projecting from said wall and having their outer edges terminating in spaced vertical planes, and another wall uniting portions only of said outer edges, said last named wall constituting a substantially flat intermediate transversely disposed bearing surface adapted to

be engaged by a movable element of the draft rigging and having curved side portions joining the shorter projecting webs.

7. A follower for draft rigging including a wall portion, a series of projecting webs 50 integrally formed with said wall portion and having their outer edges terminating in spaced vertical planes, and another wall portion uniting the outer edges of said projecting webs, an edge of said last named 55 wall being connected to the first wall by a transverse web and the intermediate portion of said last named wall forming a transversely extending bearing surface adapted to contact a movable element of the 60 draft rigging.

8. A follower for draft rigging including a wall portion, a series of projecting webs integrally formed with said wall portion, and another wall uniting the outer edges of 65 said projecting webs so as to form a transversely extending bearing surface adapted to contact and be embraced by a movable element of the draft rigging and leave a plurality of open recesses or pockets adjacent 70 said bearing surface.

9. In a draft rigging in combination, a follower including a wall portion, a series of projecting webs integrally formed with 75 said wall portion, another wall uniting portions only of the outer edges of said projecting webs for forming a transversely extending bearing surface adapted to contact a movable element of the draft rigging, means including a series of intermediate webs 80 uniting said first mentioned webs and adapted to reinforce and join said wall portions and means extending beneath said follower for supporting the same.

10. A follower for railway draft rigging 105 including a wall, a plurality of vertically and horizontally united webs integrally formed with said wall, another wall oppositely arranged to said first named wall, said oppositely arranged wall joining portions only of said vertical webs and all of 110 said horizontal webs for forming an intermediate transversely extending bearing surface adapted to contact a movable element of the draft rigging.

11. In a railway draft rigging cushioning mechanism, a yoke and a downwardly removable follower comprising a wall, a series of projecting webs integrally formed with said wall, another wall uniting the 115 outer edges of said projecting webs for forming a transversely extending bearing surface adapted to contact the yoke, and projections provided on said follower for supporting the yoke.

12. In a railway draft rigging cushioning mechanism, a yoke, and a downwardly removable follower comprising a wall, a series of projecting webs integrally formed with 120 said wall, another wall uniting the outer 125

edges of said projecting webs for forming a transversely extending bearing surface adapted to contact the yoke, and projections provided on the outermost projecting webs 5 for supporting the yoke.

13. A follower for railway draft rigging involving opposite wall portions cooperatively associated respectively with the cushioning mechanism and a movable element of 10 the draft rigging whereby one of said walls contacts said movable element transversely of the draft rigging, and a plurality of vertical webs joining said wall portions, the upper edges of some of said webs adjacent 15 one of the wall portions being inclined and uncovered to facilitate insertion of the follower plate.

14. A follower for railway draft rigging including a wall, a plurality of vertically 20 and horizontally united webs integrally formed with said wall, another wall oppositely arranged to said first named wall, said oppositely arranged wall joining portions only of said vertical webs and all of 25 said horizontal webs for forming an intermediate bearing surface adapted to engage a movable element of the draft rigging, said vertical webs being formed with a plurality of openings adapted to substantially register 30 transversely of the follower.

15. A cast follower comprising a plate member, a plurality of upright webs extending from one face of said plate member, a plurality of transverse webs extending from said face of the plate member, certain 35 adjacent pairs of said transverse webs forming pockets opening away from said plate member, and means for connecting the free ends of certain other pairs of said transverse webs and forming a wall substantially parallel with the plate member.

16. A follower for draft rigging comprising a front wall, a rear wall, and a plurality of integral upright and transverse webs joining said walls so as to form pockets 45 opening in a longitudinal direction, and pockets therebetween closed in a longitudinal direction but opening transversely.

17. A filler block and follower member for draft rigging comprising a transverse wall 50 extending the full height of the member, another transverse wall extending only part of the height thereof, horizontal and vertical webs joining said walls with some of said vertical webs tapering in width to permit 55 ready insertion of the member between the cushioning mechanism and the yoke of the draft rigging.

In testimony whereof I affix my signature.
